NAME PANEL BOARD

Carl A. P. Johnson, North Quincy, Mass., assignor to
S. H. Couch Company, Inc., North Quincy, Mass., a
corporation of Massachusetts

Application September 18, 1951, Serial No. 247,162

7 Claims. (Cl. 40—125)

The present invention relates to an indicator panel such as used in office buildings, apartment houses, hospitals and the like as a directory of the occupants.

The present invention is more particularly concerned with a panel of such a nature in which individual plates may be used for each room or apartment, which are readily removed and interchanged and are also illuminated.

It is of course essential in such a directory panel to provide easy access to the individual name plates so that they may be removed, cleaned or so that the electric bulb may be replaced if it should burn out.

It is also desirable in such a panel to have the individual plates removed from the front without opening the panel or disturbing it in any way.

It is further desirable to have an individual light for each name plate and have it arranged in such a manner so that no light will illuminate more than its own individual name plate.

In addition to the above advantages which are provided in the present invention, the invention also has constructional features by means of which the elements of the structure, particularly the individual boxes are aligned and arranged through the construction of the panel itself.

In the present invention each name plate is framed in the front end of a light box which is pressed into the panel in its proper position and all of the light boxes are nested together without any substantial separation between them. This provides a simple, inexpensive yet rugged construction which occupies a minimum of space.

The panel arrangement may be used in connection with a signaling system so that the boxes will be illuminated by manual control or otherwise when the occupants are present or under any other convenient signaling system.

Further and other advantages of the present invention will be more fully understood with reference to the specifications below when taken in connection with the drawings illustrating an embodiment of the invention, in which:

Figure 1 is a fragmentary plan view of a group of light boxes and the frame within which they are contained forming a part of the invention.

Figure 2 is a fragmentary side view of the arrangement shown in Figure 1.

Figure 3 is a slightly modified view of a detail of the invention as viewed from the bottom side of Figure 2 with a plate removed to permit the clearer showing of constructional details.

Figure 4 is a sectional view of a detail taken along lines 4—4 of Figure 3.

Figure 5 is a detail corresponding to Figure 3 of the view shown in Figure 2, and,

Figure 6 is a sectional view of a detail taken along lines 6—6 of Figure 3.

In the present invention there is provided a supporting frame 1 which is preferably rectangular in shape and in which individual light box units 2 are mounted.

The frame 1 has secured to its on the rear face, angle brackets 2 and 3, which may be welded or bolted to the

2

frame 1 or secured in any suitable manner. These may be individual brackets as shown in Figure 3, or a single bracket may extend the length of the frame on either side. Extending lengthwise of the frame, centrally between the brackets 2 and 3, is a plate 4, the sides of which are secured to the angle brackets 2 and 3 by a series of screws 9' which also hold one end of the U bracket 5.

The individual light box units include this U-shaped metallic bracket or channel element 5, the short sides or prongs of which are turned up at right angles forming angle sections as indicated by 6, 6, designating the prongs. A boss 7 is punched in the outer face of the prongs as a means for securing the box element 8 which covers the U-shaped member to it. The channel or U-shaped member 5 is secured to the brackets 2 and 3 at the outer corner by the screws 9 through the plate 4 and at the inner corner to the plate 4 by means of the screws 10' which are screwed through the rear face of the plate 4 into the cross elements 16 of each channel or U-shaped member. The box 8 is formed with an open window face 9 surrounded by a rectangular frame 10 which is provided with an upwardly extending shoulder 11 extending to the rearwardly extending walls 12 and 13 for the long sides, and 14 and 15 for the shorter end walls.

25 The box is open at the rear end as viewed in Figure 3 and the end walls 14 and 15 are not parallel but taper together in the direction of the window opening as may be seen in Figure 2.

The side walls 12 and 13 also taper in a narrowing direction towards the front window opening. The prongs 6 may be at right angles to the cross elements 5 of the U-shaped member, but in any event they are positioned at such an angle that the box 8 may be readily forced over the prongs 6 and make frictional contact at the sides 35 of the box in the region of the bosses 7.

In order to make it easy to insert the box elements over the U-shaped channel, shallow grooves 17 are made in the end walls 14 and 15 of the box. These, as seen in Figures 2 and 4, taper towards the front end of the box 40 so that a tight fit will be assured when the box is put in place. In addition, since the long walls taper towards one another, as shown in Figure 4, the end sections of the prongs of the U-shaped member 5, will fit snugly into the end walls of the box and hold the box tightly in place. 45 Resting on the inner face flange or shoulder 11 of the box, is a letter plate 18 which may be translucent or transparent and which will transmit sufficient light through it so the letters which are printed or engraved on the face of the plate 18 will be readily visible by a light 19 within 50 the box when this is lit.

On the inside of the box at each end of the long walls, there are provided two grooves, 20, 20, in which U-shaped spring elements 21, rest, the purpose of which is to hold securely in place the letter plate 18. The plate 4 carries 55 the light or other signal fixture 22 which is secured to it in a suitable manner as by the screws 23 which are tapped into the plate 4. The plate 4 has a series of large holes 22' coinciding with holes 23' in the U-shaped channel 5 so that the bulb 19 may be screwed in place simply by removing the box.

If desired the switches 24 may be provided for each of the lights or other circuit elements may be attached to the panel or frame. The whole frame may be hinged at one of the sides and be swung open from its supporting 65 cavity in a wall with all of the electrical leads attached thereto so that any change can readily be made from the rear or the front of the unit.

However it will be evident that this need not be done in order to change the name plate or to put in a new light, since all that is necessary is to remove the individual box 70 from the front of the panel by drawing it out, then change the name plate or replace the light in whatever manner

that may be required. Connections to all of the light elements are accessible by opening the frame as a whole, that is, by swinging it on its hinges.

Having now described my invention, I claim:

1. A panel board for removable insignia, comprising a frame, a plurality of channel members supported by the frame in continuous line, said channel members having angle sections at each side forming a part of the channel members, boxes having open backs and front window openings adapted to receive removable insignia, each of said boxes being of a size to have a snug fit and fitting over individual angle sections of said channel member, said boxes being nested together to form a substantially continuous panel board whereby a complete panel with removable insignia is provided.

2. In an insignia panel board, a light box unit including a U-shaped channel member, a light box having an open end on the back face and a window frame opening on the front face, a removable plate element having a size to fit in said box and fill the window opening, said channel member having side prongs forming a snug fit against the end walls of said box with the ends of the prongs substantially extending over the interior width of the box just behind the front window opening.

3. A panel board for removable insignia comprising a frame, a plurality of insignia boxes nested together side by side filling the frame, means removably supporting the boxes to the frame comprising a U-shaped channel member for each box having side prongs engaging the end walls of each box and the edges of the prongs filling against the side walls of each box, means mounting the channel members to the frame and removable insignia substantially filling the face of each box.

4. In an insignia panel board, a light box unit including a U-shaped channel member, a light box having an open end on the back face and a window frame opening on the front face, said light box having side walls sloped slightly towards one another to the front of the box and end walls also sloped slightly toward one another to the front of the box, the front of the box having a face flange extending inwardly as a border around the window opening, a removable plate element covering said window opening and resting on said flange within said box, said channel member having side prongs engaging in abutting relation

the face of said end and side walls of said box at their narrow dimensions.

5. In an insignia panel board, a light unit including a U-shaped channel member, a light box having an open end on the back face and a window frame opening on the front face, a removable plate element having a size to fit in said box and fill the window opening, said channel member having side prongs with bosses formed on the rear faces thereof, and said end walls of said box tapering towards one another towards the face of the box, whereby the bosses will engage the faces of said end walls of the boxes and provide a snug fit of the box to said channel.

6. A panel board for removable insignia comprising a frame, a pair of parallel angle bracket elements mounted on the back of the frame at the sides, a plate extending across said bracket elements, said plate having a plurality of mounting holes, a series of U-shaped bracket elements having their cross sections secured to said plate in aligned rows, a series of light boxes having open back ends and front frames for removable window plates for insignia, said light boxes adapted to have a snug fit into the prong ends of the U brackets whereby a complete panel will be made by said front frames of said light boxes.

7. A panel board comprising a mounting frame, a plate secured to said frame, having a plurality of projecting prong elements aligned in rows secured to said plate, a plurality of individual light boxes having walls adapted to engage said projecting prong elements to removably hold said light boxes in place, said projecting prong elements being positioned and said light boxes having such a size whereby the faces of the boxes form a continuous panel surface when put in place.
